1 Claim. (Cl. 60—30)

This invention relates to exhaust afterburner systems.

More particularly, this invention relates to regenerative exhaust afterburners and to manifold means therefor.

Still more particularly, this invention is directed to a flame type, flow reversal, regenerative exhaust afterburner and to an improved exhaust gas input manifold assembly therefor.

It is an object of this invention to provide an afterburner for internal combustion engines which combusts exhausted unburned or partially burned fuel.

It is another object of this invention to provide an afterburner system which is similar in back pressure to a conventional muffler system.

It is another object of this invention to provide a flame type, flow reversal, regenerative exhaust afterburner in which the particular combination of passageways and combustion chamber offers minimum back pressure to the internal combustion engine feeding its exhaust gases thereto.

It is another object of this invention to provide an improved flame type regenerative exhaust afterburner including a combustion chamber, a pair of spaced regenerative heat exchangers at each end of the combustion chamber, a conduit extending longitudinally of the combustion chamber and communicating at one end with an adjacent end of said chamber.

It is another object of this invention to provide a manifold assembly for an afterburner of the class just described having four chambers, valve means movable between alternate pairs of said chambers for achieving direct flow and reverse flow, and valve operating means for controlling valve movements.

It is another object of this invention to provide a manifold assembly for a flame type, flow reversal, regenerative exhaust afterburner including a housing, valve means, valve operating means, and control means for controlling and periodically reversing the flow of exhaust gases through the combustion chamber of an afterburner.

It is another object of this invention to provide a combination of afterburner and manifold therefor which coact to produce an afterburner system for internal combustion engines which not only very efficiently cleans up exhaust gases but also offers very low back pressure to the associated internal combustion engine.

The invention is further illustrated by reference to the attached drawings wherein:

FIG. 1 is a top plan view of an embodiment of a regenerative automobile exhaust afterburner, some parts thereof being broken away and some parts being shown in section;

FIG. 2 is a side elevational view of the embodiment shown in FIG. 1, some parts thereof being broken away and some parts being shown in section;

FIG. 3 is a view in vertical section taken on the line 3—3 of FIG. 1, some parts being shown in elevation;

FIG. 4 is a view in elevation as seen from right to left of FIG. 1, some parts thereof being broken away and some parts being shown in section;

FIG. 5 is an enlarged view in longitudinal section taken along the line 5—5 of FIG. 2, some parts being broken away and some parts being shown in section;

FIG. 6 is an enlarged view in longitudinal section taken along the line 6—6 of FIG. 2, some parts thereof being broken away and some parts being shown in section;

2

FIG. 7 is a further enlarged detailed view in vertical section taken along the line 7—7 of FIG. 1;

FIG. 8 is a further enlarged detailed view in vertical section taken along the line 8—8 of FIG. 1;

FIG. 9 is an enlarged elevational end view in detail similar to FIG. 2 showing a valve operating mechanism for the structure shown in FIGS. 1—9; and

FIG. 10 is a fragmentary view in longitudinal section of a modification of the embodiment shown in FIGS. 1—9.

Turning to the drawings there is seen in FIG. 1 an embodiment of a flame type, reverse flow, regenerative exhaust afterburner, herein designated in its entirety by the numeral 20. This afterburner 20 is seen to contain a combustion chamber 22 within a housing 21. A pair of longitudinally spaced regenerative heat exchangers 23 and 24 are positioned one in each end portion of the combustion chamber 22.

As those familiar with afterburner systems for internal combustion engines will appreciate, a flame type afterburner operates to remove the combustibles remaining in the engine exhaust gas by oxidizing in a high temperature flame reaction the hydrocarbons, carbon monoxide, and hydrogen in such exhaust gas. The dimensions and design considerations of a direct flame type afterburner of this invention must take into account a number of variables associated with the particular type of internal combustion engine with which the flame type afterburner is to be used. Such variables include concentration of combustibles in the exhaust gas, percent excess oxygen present, volume of the reactor chamber, pressure in the reactor chamber, specific reaction rate, reaction temperature, and the like.

In general, to maximize the rate of oxidation of combustibles in the exhaust gas, the highest practicable reaction temperature consistent with efficient operation, materials of construction, etc., must be maintained at all times in combustion chamber 22. Also, the percent reduction in concentration of combustibles (termed herein "clean-up") achieved in an afterburner is higher for a reaction at a fixed temperature the higher the concentration of combustibles is within the reaction chamber. Experience seems to indicate that when one is using afterburner 20 with a conventional four-stroke spark-ignition engine operating at atmospheric conditions on a premixed air-fuel mixture that reaction temperatures in the range of from about 1200° F. to 2200° F. are suitable in combustion chamber 22 using presently available materials of construction.

Although a large volume for combustion chamber 22 provides a greater gas residence time, presumably leading to greater reaction completion at a specific temperature, still the larger the chamber 22 is, the more the heat loss through housing 21, and, consequently, the lower the reaction temperature for a given type of construction. As a compromise value combustion chamber 22 can have a volume of from about 250 to 350 cu. in. of a premixed air-fuel mixture when afterburner 20 is being used to burn exhaust from a conventional four-stroke spark-ignition engine operating at atmospheric conditions.

The range of clean-up realized during residence time of exhaust gases in combustion chamber 22 is very great owing primarily to the enormous changes in the levels of combustibles and contaminants in the input exhaust gas stream. Such changes in input exhaust gas stream composition come about because of the ever changing modes of engine operation. Typical values reported for automobile engines in the literature show the carbon monoxide concentration varying from about 0.3% to 11.0%, the hydrogen concentration varying from about 0.1% to 5.0%, and the hydrocarbon concentration varying from about 135 to 9500 parts per million (p.p.m.) equivalent hexane. The range of these figures necessitates compromises in the design of the afterburner. Currently, for

example, the State of California has set the standards that the exhaust gas discharge from a vehicle shall not contain more than about 275 p.p.m. HC and 1.5% CO. For these standards, the percent clean-up required can range from in excess of 90% for some modes of operation to 0% for other modes of operation, as when the exhaust gas emission from an engine is already below these standards. When the exhaust gas input contains large quantities of combustible contaminants, reaction in the afterburner reactor chamber occurs readily and the main concern becomes limitation of temperatures, but when the reverse is true, reaction proceeds with difficulty and may even cease.

In order to cause combustion of engine exhaust gases in combustion chamber 22, supplementary air must be added to exhaust gases issuing from an internal combustion engine, such as a conventional automotive engine, before or at the time such exhaust gases enter the afterburner 20. The maximum amount of supplementary air that can be added for oxidation is limited because excessive quantities of supplementary air have undesirable side effects. Thus, excess supplementary air

- (a) tends to quench the exhaust gas stream from an engine thereby undesirably lowering its temperature,
- (b) tends to increase the flow rate through the afterburner thereby decreasing residence time in the combustion chamber 22, and
- (c) tends to dilute the combustibles in the exhaust gas thereby decreasing the overall concentration of combustibles entering combustion chamber 22.

The amount of supplementary air is controlled within limits directly related to the concentration of combustibles entering combustion chamber 22 from an engine. Sufficient air must be added to produce a stoichiometric mixture of combustibles in the exhaust gas and oxygen in the air with preferably a small excess of oxygen. It has been found that for four-stroke spark-ignition engines operating on a premixed air-fuel mixture the amount of supplementary air added can vary from between 5% to 10% of the original gas stream issue from an engine with the average quantity of supplemental air added being about 7.5% of the average gas flow. Thus, more excess air is added at low exhaust flow rates producing the desirable effect of having a higher concentration of combustibles at such time.

In afterburner 20 supplementary air is added to engine exhaust pipe 69 just prior to the point where exhaust pipe 69 is connected to afterburner 20 (see, for example, FIG. 1). The air is conveniently passed into the pipe 69 from a forced air feed pipe 70 which is forked at its end into a pair of delivery pipes 71 and 72 which bleed air into engine exhaust pipe 69 from opposite sides. Any convenient blower arrangement can be used as a means for forcing air through pipe 70 at the desired rate. Since such a blower arrangement does not constitute a part of this invention and its operation and construction is conventional, no further description of the means for supplying forced air to the feed pipe 70 is given here.

As will be observed from the figures, combustion chamber 22 is lined with a refractory wall 73 which, in the embodiment shown in the figures, is in a plurality of parts or pieces which are assembled together in place at the time of fabrication. The dimensions of the respective heat exchangers 23 and 24 and of the refractory wall 73 are so chosen that together they can be mounted within housing 21 as a single unit. Between the wall of housing 21 and heat exchangers 23 and 24, and between the housing 21 and the refractory wall 73, is placed a liner 74 which is usually of a thermally stable, insulating, resilient material such as asbestos which makes a snug fit between heat exchangers 23 and 24, refractory wall 73 and housing 21, dampens vibrational shocks to afterburner 20, and helps insulate afterburner 20 against thermal shocks. Securing the assembly comprising the

heat exchangers 23, 24, refractory wall 73 and liner 74, in place within housing 21, are, at opposite ends of the housing 21, header 28 and manifold 29, whose respective functions will be described hereinafter, and which so engage housing 21 and respective heat exchangers 24 and 23 as to hold all parts in fixed relationship to one another. Between header 28 and heat exchanger 24 is a spacer 75 and between manifold 29 and heat exchanger 23 is a spacer 76; these spacers 75 and 76 are usually of semi-rigid resilient construction and are made from a heat-resistant or even refractory material.

Positioned adjacent the outside of housing 21 and extending generally longitudinally thereof and parallel to each other, is a pair of conduits 26 and 27. Conduit 27 is open to the atmosphere at one end and joins manifold 29 at its other end. Conduit 26 at one end joins header 28 and at the other end joins manifold 29. Secured to the outer side edges, respectively, of header 28 and manifold 29, are the opposite side edges of a casing 31 which circumscribes housing 21 and conduits 26 and 27. Casing 31 is an optional feature of the embodiment shown in FIGS. 1 through 10, and serves the purposes of protecting housing 21, conduit 26 and conduit 27 from road dirt; acting as a heat shield retarding escape of heat from combustion chamber 22; and improving silencing. In general, header 28 and manifold 29 can be made from cast heat-resistant metal; housing 21 and casing 31 are made of heat resistant sheet metal; and conduits 26 and 27 are heat-resistant metal tubing. For purposes of convenience in mass production the various points of jointure are usually welded together although, as those skilled in the art will appreciate, welding, screwing and other methods of fastening can be employed.

Header 28 serves to join combustion chamber 22 (including the region at either end thereof comprised by respective heat exchangers 23 and 24) with conduit 26. Header 28 is of simple construction and merely defines the desired connecting passageway 39a between chamber 22 and conduit 26.

Manifold 29, at the other end of housing 21, serves to direct and channel exhaust gases from the engine into and through afterburner 20. Referring now in greater detail to manifold 29, it is seen that this structure has an inlet port 36, an exhaust port 37, a reverse flow part 38 and a direct flow port 39. Direct flow port 39 communicates from the housing of manifold 29 to combustion chamber 22. Reverse flow port 38 communicates from the housing of manifold 29 to conduit 26. Inlet port 36 communicates to the housing of manifold 29 from engine exhaust pipe 69. Exhaust port 37 communicates from the housing of manifold 29 to conduit 27.

The interior of the manifold 29 is divided into four interconnecting chambers. A first chamber 41 communicates with inlet port 36; a second chamber 42 communicates with reverse flow port 38; a third chamber 43 communicates with exhaust port 37; and a fourth chamber 44 communicates with direct flow port 39. Butterfly valve 46 is so mounted in the housing of manifold 29 between the chambers 41, 42, 43 and 44 that valve 46 may first be moved to partition first chamber 41 and fourth chamber 44 from second chamber 42 and third chamber 43; and then, secondly, may be moved so as to partition second chamber 42 and first chamber 41 from third chamber 43 and fourth chamber 44. To impart the desired movements to butterfly valve 46, a shaft 47 is rigidly fixed to the center of butterfly valve 46 so that when butterfly valve 46 is rotated or oscillated on the axis thereby created by means of shaft 47, valve 46 makes the desired partitioning movements between the respective four chambers.

Manifold 29 is equipped with an end wall 48 which is conveniently demountably attached thereto, as by machine screws or similar fastening means, which sit in sockets 54. Shaft 47 is appropriately journaled in end wall 48 so that when end wall 48 is mounted on manifold

29, the valve 46 is permitted to rotate or oscillate in the desired manner to provide partitioning movements within manifold 29. Shaft 47 thus extends rearwardly of end wall 48. Conveniently and preferably, the housing of manifold 29 is so constructed that the edges of valve 46 almost physically contact the respective partitioning walls of the individual chambers, so as to make as complete a partition as possible between the respective chambers during valve movements, taking into account, of course, the various coefficients of thermal expansion involved, and similar factors.

Means is secured to the exterior end of shaft 47 to rotate or pivot butterfly valve 46 from a first position partitioning chambers 42 and 43 from chambers 41 and 44 to a second position partitioning chambers 41 and 42 from chambers 43 and 44. Although any conventional means can be used to move butterfly valve 46 from one partitioning position to the second, one simple means for accomplishing such movement of butterfly valve 46 is shown in FIG. 9.

Here, the afterburner is equipped for use in an automobile having a conventional internal combustion engine and a 12-volt D.C. ignition system. The afterburner 20 is mounted beneath the body of the car being suitably strapped or otherwise secured to the frame members of the car (not shown in the drawings). While the distance between inlet port 36 and engine manifold 29 is not critical, the distance is usually, as a practical matter, of the order of five feet or so. A 12-volt D.C. motor 56 is conveniently mounted in proximity to the afterburner, for example, against a vertical side of frame members beneath the floor boards of a conventional automobile. This motor is chosen so as to have a constant speed of rotation of about 10 revolutions per minute or 1 revolution about every 6 seconds. To the shaft 57 of motor 56 is secured a timing cam 58. This cam is designed so that it causes the micro-switch 59 to close and thereby actuate a solenoid 61 for 180° of cam 58 rotation (i.e., a total interval of time equaling 3 seconds) thereby moving the valve 46 to a vertical position. Observe that solenoid 61 is positioned upon end wall 48 by the use of a solenoid mounting plate 66. When the solenoid 61 is actuated, pulling armature-equipped push rod 62 downward (in the embodiment shown in FIG. 9) crank 63 is moved downward. One end of crank 63 is pivotally connected to armature-equipped push rod 62. The other end of crank 63 is rotatably connected to the free end of crank arm 65. The fixed end of crank arm 65 is rigidly connected to the exposed end of shaft 47. When push rod 62 moves downward (in the embodiment shown in FIG. 9), crank arm 65 moves downward in a generally arcuate path against the yielding bias of coiled tension spring 64. When, after solenoid 61 is energized and armature-equipped push rod 62 has moved downward, valve 46 is moved to a vertical position. Thus, the valve 46 is moved from one partitioning position to the other once every three seconds.

Heat exchangers 23 and 24 are of conventional design. The sensible heat of the exhaust gas input stream entering combustion chamber 22 must be significantly greater than that of the exhaust gas stream leaving the engine for all cruise conditions, in order to obtain combustion and the desired clean-up in exhaust chamber 22. The temperature of the oxidation reactions in the combustion chamber 22 is derived from the transformation of the latent or sensible heat of the gas stream to some equivalent temperature rise. Thus, for example, if a reaction temperature of 1750° F. is necessary to bring about a desired reduction in combustibles and consequent desired percent clean-up, and the temperature realized from the combustion reaction in combustion chamber 22 is 250° F., then the temperature or sensible heat of the gas stream entering the reaction chamber must be 1500° F. The combustion reaction itself is thus seen to depend on the temperature of the gas entering the combustion chamber 22, the concen-

tration of oxidizable reactants and the degree of clean-up or decomposition desired. Actually, experience shows that a large fraction of the total exhaust gases issuing from a cruising automobile, for example, is relatively low in concentration of combustible contaminants. Consequently, one must in some manner add sensible heat to the exhaust gas input to the afterburner because the combustion reactions are not self-supporting.

The necessary sensible heat is added by the use of heat exchangers 23 and 24, which are recuperative. That is, such heat exchangers can be first heated, then cooled and reheated again, cyclically, by alternately passing heated gases therethrough crosswise, first in one direction, and then passing cooler gases to be heated therethrough in the reverse direction. Suitable heat exchangers for use in the afterburners of this invention can be designed using any suitable configuration or construction. The interaction between the regenerative heat exchangers and combustion in the combustion chamber in an actual afterburner is extremely difficult to express or describe owing to the large number of parameters involved. Indeed, the combustion process and interrelationship between combustion chamber and heat exchangers is best understood by using specific operating modes. It follows that there are many variables which enter into the selection in any given instance of a particular heat exchanger for any given regenerative flame-type afterburner of this invention. The exact size, heat capacity, mass, etc., of a heat exchanger for use in an embodiment of this invention must take into account the special circumstances of the individual case, in accordance with conventional engineering know-how. Actual selection of a heat exchanger for any given afterburner system of the invention is a matter within the province of ordinary engineering skill, to be determined in accordance with the requirements of a particular use situation. Since the structure, construction and characteristics of the heat exchangers 23, 24, are conventional and do not form a critical part of the present invention, no further description of them is needed or given here.

A conventional glow-plug or spark plug 77 is provided for the interior of combustion chamber 22 so as to provide initial ignition means for gases to be oxidized in combustion chamber 22. In the embodiment shown in FIGS. 1 through 9, this glow-plug 77 is of conventional type and is mounted through a hole extending through casing 31 (if present), housing 21, liner 74 and refractory wall 73. The glow-plug 77 is positioned in place by means of a mounting plate 78 through which the glow-plug extends normally. The mounting plate is secured in place by any conventional means, for example, by bolts threading casing 31 and, if desired, also housing 21.

In the modified embodiment partially shown in FIG. 10, a casing 32 not only serves as a shield against road dirt but also serves as a passageway for exhaust gases leaving said manifold 29. Thus, instead of the exhaust gases leaving manifold 29 entering an exhaust conduit 27, they enter directly the passageway or plenum space 32 lying between housing 21 and casing 32. In this modified embodiment, use is made of the exhaust gases to heat the exterior walls of housing 21 so as to conserve heat. A short pipe 34 is then provided to conduct exhaust gases from a passageway 33 to the atmosphere.

In general, over-capacity in the heat exchanger contributes to over-temperaturizing in the combustion chamber 22 at any given specific mode, thereby producing excessive available thermal energy for heat transfer in the region of the combustion chamber 22. The overall effect is a pyramiding process which leads to temperatures in the combustion chamber 22 far in excess of temperatures which the heat exchangers 23 and 24, refractory wall 73 and other afterburner parts will withstand. Consequently, in the interest of longevity, it is desirable and even necessary, depending upon the particular embodiment and use situation involved, to have a fail-safe means

which will control the maximum temperature in the region of the combustion chamber 22 (including heat exchangers 23 and 24). Usually, such a fail-safe means involves a bypassing of exhaust gases so that they do not pass through combustion chamber 21 or heat exchangers 23 and 24. Any convenient device can be used to provide the fail-safe means; for example, a red light or meter can readily be mounted on the dashboard of an automobile to indicate combustion chamber temperatures. If the temperature exceeds a predetermined maximum, a switch causing exhaust gases to bypass an afterburner 20 can be manually closed. Thermocouple means can be employed to automatically achieve fail-safe means.

In the embodiments shown in FIGS. 1-10, exhaust gases are readily bypassed as they enter manifold 29 from engine exhaust pipe 69 by simply providing valve shaft 47 with means turning the valve to a position midway between that in which first chamber 41 and third chamber 43 are positioned from second chamber 42 and fourth chamber 44. In other words, the valve 46 is set at an angle of 45° with respect to its normal partitioning position wherein first chamber 41 is partitioned from second chamber 42. When the valve 46 is in this 45-degree position, exhaust gases pass directly from inlet port 36 to exhaust port 37 and do not enter either reverse flow port 38 or direct flow port 39 (i.e., the gases take the path of least resistance).

The operation of the afterburner is as follows: The exhaust gas input stream (properly admixed with supplementary air) enters manifold 29 through inlet port 36. The motor 56 is operating so that the butterfly valve 46 is going through its partitioning movements of the chambers 41, 42, 43 and 44. In that position where first chamber 41 and second chamber 42 are partitioned from third chamber 43 and fourth chamber 44, the exhaust gas input stream enters first chamber 41, passes into second chamber 42 and into conduit 26. At the other end of conduit 26, the exhaust gas stream enters header 28 which directs the exhaust gas stream into heat exchanger 24, which has its longitudinal passageways aligned to permit the exhaust gas stream to pass therethrough into exhaust gas chamber 22. Since the temperature initially in combustion chamber 22 is too low for self- or auto-ignition to occur, the glow-plug 76 is ignited, as by causing a spark gap across the ends of the same to be developed. The combustible mixture in combustion chamber 22 then ignites, the gases burn, and their temperature rises. As the gases continue on their way, they reach heat exchanger 23, whose longitudinal passageways are aligned to permit the so-combusted exhaust gas stream to pass therethrough.

After passing through heat exchanger 23, the combusted exhaust gases enter fourth chamber 44 of manifold 29 through direct flow port 39. The gases then pass from fourth chamber 44 to third chamber 43, through exhaust port 37 connecting with third chamber 43 and into conduit 27, through which the combusted exhaust gases stream and pass through the open end thereof into the atmosphere.

Now, when the butterfly valve moves to its second or alternative position, as shown by the dotted lines in FIG. 7, wherein first chamber 41 and fourth chamber 44 are partitioned from second chamber 42 and third chamber 43, the entering or input exhaust gas stream passes from inlet port 36 through first chamber 41 into fourth chamber 44 and through direct flow port 39. The gases then pass in a reverse direction through heat exchanger 23 and into combustion chamber 22. Because heat exchanger 23 has been preheated by the passage of the combusted exhaust gases therethrough moments before, the entering exhaust gas stream is heated. Commonly, the so-heated heat exchanger heats the entering uncombusted exhaust gas stream to auto- or self-combustion tempera-

tures so that the gases reach combustion temperatures as they pass therethrough and burn usually mostly within combustion chamber 22. As the heated combusted exhaust gases continue on their way they pass through heat exchanger 24, thereby heating the same. These gases, after leaving heat exchanger 24 enter header 28, pass into conduit 26 and return to manifold 29, through reverse flow port 38. The gases cross over from second chamber 42 to third chamber 43 from whence they pass through exhaust port 37 into conduit 27 and finally pass to the atmosphere through the open end of conduit 27, thereby completing the cycle.

A modified embodiment of that shown in FIGS. 1 through 9 is shown in FIG. 10. Here, casing 32 has added functional significance in that it serves as a passageway for exhaust gases leaving the exhaust port 37 of manifold 29. Thus, instead of the exhaust gases leaving manifold 29 and entering conduit 27, they enter directly the passageway or plenum space 33 lying between housing 21 and casing 32. In this modified embodiment, use is made of the exhaust gases to heat the exterior walls of housing 21, thereby conserving heat. A simple, short tail pipe 34 is then provided to conduct exhaust gases from passageway 33 to the atmosphere.

An important feature of this invention is that the afterburner system minimizes back pressures upon the associated internal combustion engine. The practical range of back pressures in the exhaust system which can be tolerated by an internal combustion engine without decreasing to uselessly low levels engine efficiency, is limited, owing not only to consequential horsepower loss, but also to the difficulty of introducing supplementary air into the exhaust gas stream entering an afterburner. As a practical matter, combustion chamber pressures in an afterburner cannot be allowed to vary significantly therein, and hence pressure consideration must not be a significant variable in the operation of an exhaust afterburner, and must be substantially or as near to atmospheric pressures as possible. The afterburner system of this invention minimizes back pressures and keeps engine efficiencies generally at the same levels as are customarily associated with conventional mufflers.

A major advantage of the present invention is that the afterburner system occupies a total volume of space approximating that of a conventional automobile muffler and at the same time has back pressures of the same order as those associated with such conventional exhaust mufflers.

The invention is further illustrated by reference to the following example.

Example

The operation of an afterburner system of this invention will now be described. An afterburner system constructed in accordance with the (unmodified) embodiment of FIGS. 1-10 is chosen. The combustion chamber 22 of the afterburner in this system has a volume of about 135 cubic inches and is 9 inches in length excluding the regions of the heat exchangers 23 and 24. Each individual heat exchanger 23 and 24 is shaped in the form of a body having a generally elliptical cross-section except that opposed ends along the major axis are truncated symmetrically in directions generally normal to the major axis. Each truncated edge is 3 in. in width and the distance across the minor axis is about 4 in. while the distance between the truncated ends is about 5 1/2 in. along the major axis. Each heat exchanger 23 and 24 has a ceramic honeycomb core having a pitch of 0.15 in., amplitude of 0.035 in. and a wall thickness of approximately 0.010 inch. The thermal conductivity is approximately 4.5 B.t.u./hr./ft.² and the coefficient of thermal expansion perpendicular to the honeycomb is 2.43×10^{-6} in./in. °F. between 800° F. and 1400° F. and parallel with the honeycomb 2.33×10^{-6} in./in. °F. between the same limits. The open area of an individual core is 60%. However, if two cores are used to form one heat ex-

changer, they could be completely misaligned so as to provide only a 36% open area.

The cross-sectional area of each conduit 26 and 27 is about 3½ sq. in. The minimal cross-sectional area in the manifold in the chamber spaces between inlet port 36 and exhaust port 37, reverse flow port 38 and direct flow port 39 is generally never less than about 4 sq. in.

This afterburner is connected by means of an engine exhaust pipe to a conventional gasoline engine of the type used to power a typical American passenger car, specifically, a 283 cu. in. V-8 engine rated 160 H.P. output at 4200 r.p.m. whose intake manifold vacuum at 50 m.p.h. is about 14.5 in. of mercury.

A steady state engine condition is selected, to wit, 25.8 H.P. output at 2150 r.p.m. which corresponds to a typical passenger car cruising on a level road at 50 m.p.h. To provide oxygen for combustion 8.5 c.f.m. of fresh air is added to the exhaust flow (roughly 37.5 c.f.m. at standard conditions) ahead of the afterburner. A total flow at standard conditions of 46 c.f.m. at exhaust gas temperature, 750° F. With valve 46 in horizontal position (see FIG. 7), flow is then through front heat exchanger 23. Heat is transferred from the heat exchanger 23 to the flow, whereupon the mixture burns in the combustion chamber 22 and reaches temperatures of 2200° F. The flow then continues through the rear heat exchanger 24 giving off heat increasing the temperature of heat exchanger 24 and decreasing the temperature of the flow to 1000° F. The flow then travels back through the conduit 26 and past valve 46 and to the atmosphere. After approximately 3 seconds in the horizontal position, the valve 46 is changed to the vertical position causing the flow to reverse itself and then repeating the process above. Three seconds has been chosen as the time interval since any longer period will result in the exchanger having insufficient heat to provide high enough temperatures for combustion. Initially, when the heat exchangers are cold, the combustion is started by the spark plug. Once started the spark is not necessary.

The pressure drop under the conditions described across the entire afterburner is 1.4 in. of mercury. Of this 0.9 in. of mercury occurs across the heat exchangers and combustion chamber. The untreated inlet hydrocarbon content was 375 p.p.m. and the CO content was 3.9%. After further combustion within the afterburner, a value of 80 p.p.m. hydrocarbon and 0.5% CO was achieved.

In summary, the present invention is directed to a regenerative afterburner for exhaust gases from internal combustion engines comprising elongated housing means defining a combustion chamber, a pair of longitudinally spaced regenerative heat exchangers each disposed in a different end portion of said chamber, conduit means extending longitudinally of said housing means and communicating at one end with an adjacent end of said chamber, a manifold included in said housing means at the other end of said chamber and having inlet port, exhaust port, and reverse flow port communicating with the other end of said conduit means, and a direct flow port communicating with said other end of said chamber, valve means in said manifold and including a valve element movable between direct flow and reverse flow positions, said valve element in its direct flow position effecting communication between said exhaust and reverse flow ports, said valve element in its reverse flow position effecting communication between said inlet and reverse flow ports and between said exhaust and direct flow ports, valve operating means for shifting said valve element between said positions thereof, and gas combustion initiator means in said chamber.

The invention also relates to a manifold for a flame type regenerative afterburner, said afterburner including elongated housing means defining a combustion chamber and conduit means extending longitudinally of said hous-

ing means and communicating at one end with one end of said combustion chamber, said manifold comprising a manifold housing defining an inlet port for receiving exhaust gas input, an exhaust port communicating with the atmosphere, a reverse flow port communicating with one end of said conduit means, and a direct flow port communicating with the other end of said afterburner housing, said manifold housing further defining four interconnecting chambers, a first of which communicates with said inlet port, a second of which communicates with said direct flow port, a third of which communicates with said reverse flow port, and a fourth of which communicates with said exhaust port, valve means in said manifold and including a valve element shiftable between spaced operative positions, said valve element in one of said positions establishing communication between said first and third chambers and between said second and fourth chambers and in the other of said positions establishing communication between said first and second chambers and between said third and fourth chambers, valve operating means for shifting said valve element between said operative positions thereof, and control means periodically rendering said valve operating means operative to shift said valve.

Although the foregoing description has been made with reference to certain preferred embodiments of the invention, it will be appreciated that the afterburner system and, in particular, the exhaust afterburner itself and the manifold therefor, can be used with substantially any internal combustion engine. Thus, the invention is not restricted to use with conventional four-stroke spark-ignition engines operating at atmospheric conditions, or conventional fuels therefor, but can be used with any internal combustion engine using vaporizable or air-dispersable, oxidizable fuel. More broadly, the afterburner and manifold of this invention can be used in any situation where one desires to oxidize a combustible fuel mixture in order to avoid releasing such mixture to the environment. The references in the specification to operating conditions and design considerations for the afterburner system of this invention are for purposes of illustration only, and do not constitute any limitation upon the inventive subject matter of this application as set forth in the appended claim. It is to be understood that this invention is capable of modification without departure from the spirit and scope of such appended claim.

I claim:

A regenerative afterburner for exhaust gases from an internal combustion engine comprising an elongated housing, a pair of regenerative heat exchangers fixedly mounted in longitudinally spaced relation in the housing, a manifold having an inlet mounted on one end of the housing engaging one of said pair of heat exchangers, a header mounted on the opposite end of the housing engaging the other of said pair of heat exchangers, and a spacer ring of refractory material between and in engagement with said heat exchangers, valve means in the manifold, conduit means connecting the header and manifold, and means for periodically shifting said valve means to alternately connect the inlet of the manifold to one end of the first heat exchanger and connect one end of the conduit means to exhaust and to then connect said one end of the first heat exchanger to exhaust and the conduit to the intake whereby to provide for a straight line flow of gases through the heat exchangers first in one direction and then in the opposite direction.
